Primary Examiner — Calvin E Vansant*Assistant Examiner* — Giang Hoang Tran(74) *Attorney, Agent, or Firm* — Schwabe, Williamson & Wyatt, P.C.(57) **CLAIM**

The ornamental design for a front bumper for a vehicle, as shown and described.

DESCRIPTION

FIG. 1 is a left front perspective view of the front bumper for a vehicle;

FIG. 2 is a front view thereof;

FIG. 3 is a back view thereof;

FIG. 4 is a top view thereof;

FIG. 5 is a bottom view thereof;

FIG. 6 is a right side view thereof; and,

FIG. 7 is a left side view thereof.

The broken lines in the drawing depict portions of the front bumper for a vehicle that form no part of the claimed design.
